UNITED STATES PATENT OFFICE.

CLAUS DIETRICH, OF ST. PAUL, MINNESOTA.

LOCK.

Application filed May 8, 1925. Serial No. 28,813.

My invention relates to improvements in locks and is particularly adapted to that style of lock used for safety deposit boxes and the like where two keys are employed, 5 one of which is the bank pass key, while the other is the key of the party renting the safety deposit box.

My invention includes means designed to provide a safety which is particularly 10 adapted to a double barrel lock where two keys are employed, it being necessary that one key be inserted into the lock before the other key can operate. While locks are designed to operate in this manner and are 15 now on the market, these locks are not pick proof, as it is possible to insert a pick in the key-way passage and by properly manipulating the same the tumbler or operating dogs of the lock can be raised in a manner so that the lock can be opened by picking it through one of the key cylinders and using a key in the other cylinder. My invention is designed to overcome this objectionable feature of present locks by a 20 simple, inexpensive means which is readily adapted to the present construction and formation of locks.

A further feature of the invention resides in providing a safety plate means 25 which can be stamped out of sheet material and which is adapted to fit in the present formation of locks of this type in a manner so as to cooperate with the key cylinders and the lock operating dogs or tumblers so that the lock can only be operated by a pass key held by the bank and the key of the safety box owner, thus preventing any possibility of picking the lock or opening it with a knife blade, as is possible with certain forms of locks now in use.

A further feature of the invention resides in separate blade means which is positioned in the lock and which is adapted to operate in conjunction with both of the key cylinders, thus making it necessary to have a key for the pass key of the lock, which will operate both of the plate means at the same time and thus release the cylinder for the key of the party having the safety deposit box.

Locks of the kind described are in general use in safety deposit banks now and it is desirable to provide a lock which is adapted to insure the party renting the box 55 that it is safe against being tampered with, thus making it necessary that the bank key

operate just as perfectly as the key of the renter.

These features, together with other peculiar formations and other objects will be 60 more fully set forth in the specification and claims:

In the drawings forming part of my specification;

Figure 1 is an illustration of the ordinary lock used for safety deposit boxes, 65 showing a form of my invention associated therewith.

Figure 2 is a view of a similar lock illustrating a form of my invention attached 70 thereto, the cover plate of the lock being removed in this illustration.

Figure 3 is a section on the line 3-3 of Figure 2.

Figure 4 is a section on the line 4-4 of 75 Figure 2.

Figure 5 illustrates a detail portion of my invention.

Figure 6 is an end view of the part illustrated in Figure 5. 80

Figure 7 illustrates one of the key cylinders removed from the lock.

Figure 8 illustrates another of the key cylinders removed from the lock.

Figure 9 is a plan view of one of the 85 safety plates used in the lock.

Figure 10 is an end view of the same.

Figure 11 is a view of the other safety plate.

Figure 12 is a bottom view of the plate 90 illustrated in Figure 11.

Figure 13 is an end view of the plate illustrated in Figure 11.

Figure 14 illustrates a form of cylinder with the wire connection on the side of 95 the same.

Figure 15 is a plan view of a form of the safety plate.

Figure 16 is a side edge elevation of Figure 15. 100

In the drawings the lock A is provided with a casing B in which the lock bolt C is adapted to operate. The locking bolt C is controlled by a series of lever tumblers 10 which are held by the springs 11 in a manner to normally hold the bolt C in locked position. The bolt C cannot be unlocked and turned to withdraw the same into the housing B of the lock A until the proper keys are inserted through the key revolving 105 plugs or key cylinders 12 and 13. This lock is of the lever tumbler type and is the de-

sign of lock as is ordinarily used in safety deposit boxes in banks and such places. These types of locks are made with a pair of key plugs which are adapted to revolve when the proper key is inserted therein to release the mechanism in the lock, the plug or cylinder rotating with the key to operate the lock tumblers.

In carrying out my invention I provide safety plate members 15 and 16 which are superimposed in the lock housing B as illustrated in Figures 3 and 4. The plate 16 is adapted to lie against the bottom 17 of the housing B while the plate 15, which is of an angular cross section, is superimposed above the plate 16 and the side wall 18 of the member 15 depends downwardly and engages freely against the surface of the bottom 17. The side wall 18 is designated to rest against the side wall 19 of the housing B and the shank 20 of the plug 13 is adapted to extend through the opening 21 formed in the plate 15. This holds the plate in place in the lock A with its side wall 18 against the upwardly extending wall 19 of the housing B and with the lower edge of the wall 18 resting on the face of the bottom 17.

The opening 21 in the plate 15 is elongated to permit the plate to slide longitudinally when the key is inserted in the plug 13 and engaged by the key to operate the plate. To normally hold the plate with its edge 22 against the side wall 23 of the housing I provide a wire spring arm 24 which is attached at 25 by a screw or other suitable means to hold the wire spring arm 24 in position, so that it will engage against the surface of the shank 20 of the plug 13. This holds the plate member 15 normally out of operating position with its edge 22 against the side wall 23 of the lock A.

The plate 15 is formed with a hook 26 by stamping out the material which is of a particular shape, having a recess 27. The hook 26 is adapted to engage the wire loop 28 formed on the plug 12 so that in normal position the loop 28 is engaged in the recess 27 in a manner so that when the member 15 is in the position illustrated in Figure 2 with its edge 22 against the wall 23 the cylinder or plug 12 cannot be rotated to operate the lock A.

The plate 16 is similar to the plate 15 in outline, excepting that it does not have the depending wall 18, and it is provided with a cylinder opening 29 which is similar to the opening 21, while the key operating opening 30 extends from the opening 29. A hook 31 similar to the hook 26 is formed on the end of the plate 16 and a recess 32 conforming with the recess 27 is also in the construction of the hood. This hook 31 is adapted to engage the wire arm 33 so that the arm 33 extends in the recess 32 and

permits the hook 31 to hold the cylinder or plug 12 from turning even though the plate 15 might have been operated to a position to disengage the hook 26 from the loop 28. This plate 16 is directly below the plate 15 and is a complementary member adapted to cooperate with the same when the proper key is used so that the plates 15 and 16 operate together in a manner to release the loop 28 and the arm 33 so that when the proper key is inserted in the key slot 34 of the plug 12 the same can be rotated and the tumbler levers 10 operated to operate the bolt C of the lock A.

In operation the bank is adapted to insert their key in the key slot 35 in the plug 13 and this key is formed with the proper notches so as to operate the safety plates 15 and 16 to move the same longitudinally so that the hooks 26 and 31 disengage the loop 28 and the arm 33. If the bank has the proper key the two safety plates 15 and 16 will be readily operated, but unless the proper key is used it is practically impossible to insert a pick or member into the key slot 35 and operate the tumbler levers 10. When the plates 15 and 16 are properly operated the proper key can be inserted into the key slot 34 and this cylinder or plug 12 is free to rotate in a manner to permit engagement of the tumbler levers to operate the same and operate the bolt C of the lock.

The plates 15 and 16 are stamped out of sheet material and are of an inexpensive construction, while the loop 28 and the arm 33 are the only additional elements to the lock to provide a safety which prevents a knife blade to be inserted through the key slot 35 to operate the lever tongues 36, which are formed integral with a pair of the lever tumblers. Heretofore these locks of this design have been made without any means of providing a safety such as I have illustrated, and thus by inserting the blade of a knife or other suitable lock pick instruments the lever ends 36 could be engaged and operated and thus the cylinder 34 could operate to work the bolt C of the lock A. My invention is designed to overcome this difficulty in a simple inexpensive manner and to provide a pair of plate members which must operate in unison and which it is practically impossible to operate unless the proper key is used with the notches formed therein to conform with the position of the recess 30 and the key recess 37. The hook engagements of the plates 15 and 16 are independent of each other and thus even though the one plate may be operated it is not possible to operate the plug 12 unless the other plate is operated, thus providing a safety for the double plug lock A.

A simple, yet effective, safety device is illustrated in Figures 5 and 6 of my draw-

ings in which I illustrate a safety member D which is channel shaped and is provided with an upper plate 38 and a bottom plate 39 positioned directly below the plate 38, 5 while the front plate 40 rests against the front or side 19 of the lock housing B. This safety member D is provided with plug openings 41 in the upper and lower plates 38 and 39 and extending from these openings are the key recesses 42 and 43 which are of an oppositely positioned nature in relation to each other and are of a different shape so that the plug 13 cannot be rotated unless a key conforming with these notches 10 and openings is inserted into the key slot 35 of the plug 13. This safety functions similar to the plates 15 and 16, yet the members 38 and 39 are connected together by the side 40 and are operated together. This 20 form of device is not as preferable as the plates 15 and 16, yet it is operable to form a safety for the lock A of a very simple nature, so that it cannot be easily picked and is not operable with an ordinary knife 25 blade.

In making my device I can make the cylinder 12, which receives the key in the key slot 34, with the wire loop 50 which operates similar to the loops 28 and 33 excepting that the loop 50 is made in a single piece and otherwise the cylinder 12 illustrated in Figure 14 is of the same construction as that illustrated in Figure 7, having the same function. The wire 50 engages in the hook portions 32 and 27 of the plates 15 and 16.

In making the cylinder 12 with the single wire loop 50 it is preferable to form the plate 16 as illustrated in Figures 15 and 16, 40 with an offset portion 51, which sets the hook recess 32 with the hook end 31 up above the base 17 of the housing of the lock A. This permits the free connection of the recess 32 of the hook end 31 with the loop 50. However, the plate 16 illustrated in Figures 15 and 16 operates in the self same manner as the plate 16 in Figures 9 and 10. I add the wire spring member 24' on the member 16 in Figures 15 and 16 to 50 assist in holding the plate 16 in one direction in relation to the connecting parts in the same manner as the spring arm 24 holds the plate 15 in operation.

In accordance with the patent statutes I 55 have described the principles of operation of my invention, together with the best embodiment thereof, but I desire to have it understood that these illustrations and drawings are only suggestive and that this invention can be carried out by other means and applied to uses other than those above set forth within the scope of the following 60 claims:

I claim:

1. A lock including a pair of key plugs,

lever tumblers operable by keys adapted to fit into said plugs, one of said plugs forming means for receiving a pass bank key and the other of said plugs being operated by the key of an individual and safety plate 70 means associated with said plugs in a manner to be operated in unison to release the key plug for the individual and a key for operating the same by releasing the safety means from said plug by the bank pass key. 75

2. A lock of the lever tumbler type including a series of lever tumblers, a pair of key plugs associated with said lever tumblers in a manner so that one of said plugs must be operated before the other can operate and means comprising super-imposed plate members having key slots formed therein which require a key made to fit said slots so that said plate members can operate in unison to 80 release the plug which is adapted to operate the lever tumblers and bolt of said lock. 85

3. A lock of the lever tumbler type, a key plug for operating the majority of the lever tumblers of said lock and the bolt of the same, a second key plug adapted to form the releasing means to permit said first key plug to be operated when the proper key is inserted therein and super-imposed plate means associated with said second key plug, 90 having key slots of a different formation formed therein, whereby said second key plug can only be operated by a key designed to fit the recesses in said super-imposed plate means. 95

4. A lock of the double key plug type, having a series of lever tumblers, said tumblers being operable by keys and plate safety means associated with key plugs in a manner so that when one of said plugs operates said plate means when the proper key is used therein the other of said plugs is released so that it may be operated by the proper key to fit said lever tumbler members. 100

5. A lock including a pair of key plugs, one of said plugs forming a releasing means to permit the other of said plugs to be operated, a pair of plate members carried by said releasing plug, hook members formed on the end of said plates, loop means formed on the other of said plugs to be engaged by said hook members to hold said second plug from operation until said first plug has been operated by the proper key to fit said plate members, said plate members being independent of each other and having key slots of a different design, said plate members unlocking said second plug to permit the same to rotate. 110

6. A safety device for a lock having a pair of key plugs including an angular shaped plate-like member adapted to be carried by one of said plugs, hook means formed on the end of said plate member, spring means adapted to hold said plate member in 125 130

4
one position on said plug, a second plate member positioned below said first plate member carried by said key plug, a similar hook means formed on said second plate member, the hook means of both of said plate members being adapted to engage means formed on said second key plug member, whereby when said safety plate members are operated by the proper key in the first plug said second plug is released so that it can be rotated to operate said lock.

7. A safety for a lock having a pair of key plugs, including superimposed plates having hooks formed on one end thereof, one of said plugs of said lock adapted to extend through said plates, the other of said plugs carrying members adapted to engage with said hooks to lock it from operation, whereby when the key is inserted in the

20
plug carrying said plates, and operated, said plates are moved longitudinally to unlock the hooks from said second plug to permit the same to be operated to operate said lock.

8. A safety means for a key operated lock comprising a pair of key plugs in said lock, super-imposed plate members adapted to be operated through one of said plug members, said plate members having different key slots therein whereby the plate members can be operated only by a key designed 30
25
to fit said key slots.

9. A lock of the lever tumbler type comprising a pair of key plugs therein, safety means connected to said key plugs and means carried by said safety means preventing the operation of one of said key plugs until said safety means has been operated. 35
